BOOK LAMP

Jacob Cohen, Los Angeles, Calif., now by judicial
change of name Jack Victor Conway

Application June 22, 1942, Serial No. 447,894

5 Claims. (Cl. 240—6.4)

This invention relates to portable illuminating means and relates more particularly to a book lamp for illuminating the pages of a book. A general object of this invention is to provide a practical, effective and convenient book lamp.

Another object of the invention is to provide a lamp that may be readily applied to or associated with a book, or the like, and that is operable to effectively illuminate the pages of the book as they are successively turned for use or reading.

Another object of this invention is to provide a book lamp that serves to hold the book open and yet allows free ready turning of the pages and free bodily movement of the book, while effectively illuminating the pages or selected portions of the successive pages.

Another object of this invention is to provide a book lamp in which the source of illumination may be adjusted or shifted in practically any direction to obtain the required or preferred illumination and to avoid undesirable glare from the pages. The illuminating means may be shifted back and forth across the top of the book, may be adjusted toward and away from the pages, may be bodily swung about an axis and its reflector may be extended and retracted and directed as desired to obtain any required or preferred illumination of the individual pages or of the two adjacent open pages or parts thereof.

Another object of this invention is to provide a book lamp that may be bodily shifted or adjusted to assume a position where the book may be opened or closed at will and where the book may be stacked with other books without interference.

Another object of the invention is to provide a device of the character described in which the switch means for the lamp is automatically controlled by moving the reflector between the retracted and extended positions.

Another object of this invention is to provide a book lamp that contains or carries its own source of electrical current and, therefore, does not require a cord or wire. The illuminating device of the present invention embodies a battery or batteries so that it does not need a cord or wire but may embody a plug or socket so that the device may be connected with a house lighting source, or the like, if desired.

A further object of this invention is to provide a book lamp that is light in weight and compact and very easily applied to and removed from the book.

The various objects and features of my inven-

tion will be readily understood from the following detailed description of a typical preferred form and application of my invention, throughout which description reference is made to the accompanying drawing, in which:

Fig. 1 is a front elevation of the device provided by this invention in the operative position on a book with the lower portion of the book broken away. Fig. 2 is a top or plan view of the device on the book. Fig. 3 is an enlarged vertical detailed sectional view taken as indicated by line 3—3 on Fig. 1. Fig. 4 is an enlarged fragmentary horizontal detailed sectional view taken as indicated by line 4—4 on Fig. 1, and Fig. 5 is an enlarged fragmentary longitudinal detailed sectional view illustrating the switch means for controlling the lamp.

The portable illuminating means of the present invention is suitable for use on various devices, for example, it may be used on books, writing pads, folders, musical scores, etc. Accordingly, where I herein employ the term "book" it is to be understood that I mean to include similar objects such as catalogs, writing pads, folders, musical scores, etc.

The lamp or illuminating means of the present invention may be said to comprise, generally, a mounting means 10 adapted to be applied to a book B, or the like, and operable when desired to hold the book open, a shell or body 11 carrying a battery or batteries 12 and a lamp 13, means 14 connecting the body 11 with the mounting means 10 for adjustment in various directions and a reflector 15 for the bulb or lamp 13 adjustably and retractably supported on the body 11.

The mounting means 10 is operable to support the device on the book B and may embody means for holding the book open with the pages P spread apart for use. The mounting means 10 is characterized by its simplicity, comprising a mounting plate 16 adapted to be engaged behind the book B and a flange 17 which extends along the upper edge of the plate 16 to engage over the upper end of the book B. The plate 16 may be a simple flat member and may have a curved lower edge. The flange 17 is normal to the plate 16 and is of substantial length so that it may engage over the upper end of the book B at opposite sides of the book binding. Depending lugs or ears 18 are provided on the flange 17 and in the particular construction illustrated are engageable with the pages P to hold the pages down or open. There may be an ear 18 at each end of the flange 17 and the ears are spaced

apart so that they engage the pages *P* at a substantial distance from the book binding when the device is in a central position, such as illustrated in Figs. 1 and 2.

In accordance with the invention the ears *18* are formed so that a page *P* may be individually freed from under one ear *18* for turning and then reentered under the other ear. The ears *18* are shaped to present convex under or inner surfaces *19* for contacting the pages *P*. As illustrated in the drawing the ears *18* are arcuate in transverse cross section to have the desired convex active surfaces. The ears *18* preferably have rounded lower edges and their lower ends may be shaped to facilitate the withdrawal and insertion of the pages *P*. It will be seen how the individual pages *P* may be disengaged from one ear *18* and entered under the other ear *18* as the reading or use of the book progresses. It is to be understood that the flange *17* and the ears *18* are formed so that the device may be readily moved or slid along the book *B* to any selected position. The plate *16*, the flange *17* and the ears *18* may be a single integral unit and may be formed of plastic, sheet metal, or the like.

While I have shown two ears *18* rigid with the flange *17* it is to be understood that there may be only one ear *18* and that the ear or ears, as the case may be, may be separately formed parts and may be flexible and shiftable to readily engage with books of different sizes and to cooperate with the pages in the front, intermediate and rear portions of the opened books. It will be observed that the ears *18* assist in retaining or securing the device on the book, serving as hooks or anchors that prevent rearward displacement and tipping of the device. The invention contemplates that the ears *18*, or their equivalents, may be formed and located to cooperate with the binding or cover of the book instead of the pages *P*, the cooperation with the book cover or binding serving to hold or retain the device on the book. In any case the ears are such that the lamp or device may be readily applied to the book, adjusted along the book and detached from the book.

The shell or body *11* carries the battery *12*, the globe or lamp *13*, the reflector *15* and other parts. The body *11* is an elongate hollow or tubular member of suitable proportions and finish. The body *11* may resemble the body of a conventional flashlight and its outer end is normally closed by a threaded-on cap *20*. The battery *12* is slid into the outer end of the tubular or shell-like body *11* and its inward movement is limited by an internal bead *22* of the body. A spring *23* is arranged under compression between the cap *20* and the outer end of the battery *12*. In accordance with the usual practice in devices of this nature one pole of the battery is grounded to the body *11* through the spring *23*. The other pole or post *24* of the battery *12* is exposed at the inner end of the battery.

The forward or inner end of the body *11* carries a suitable socket *25* for receiving the stem *26* of the lamp *13*. The socket *25* is preferably in electrical connection with the body *11* and, therefore, is electrically connected with the "grounded" pole of the battery *12*. A suitable switch means is provided to electrically connect the other pole *24* of the battery *12* with the terminal of the lamp *13* to complete the circuit through the lamp. This switch means may take various forms. The switch means is operated by

or under the control of the reflector *15* to cause energization of the lamp *13* when the reflector is extended for use and to cause deenergization of the lamp *13* when the reflector is shifted to the retracted position. The switch means will be hereinafter described.

If desired, the body *11* may be equipped with means whereby the device may be connected with an outside source of electrical energy such as the lighting circuit of a residence. For example, as illustrated in Fig. 2 of the drawing, the body *11* may have a socket *33* on its side adjacent its inner end for receiving a pronged plug of a light cord. The socket *33* has its terminals electrically connected with the body *11* and with the contact button *28* at the terminal of the lamp *13*. Where a conventional light source is plugged into the plug *33* it is usually necessary to interpose a suitable transformer between the plug and the source to step down the voltage.

The means *14* operates to mount the body *11* on the mounting means *10* in such a way that the body and the parts carried thereby may be adjusted back and forth in the direction of the arrow *Z*, in and out in the direction of the arrow *Y*, and about a central pivot as illustrated by the arrow *X*, all in Fig. 2. The means *14* includes a pair of complementary links *34* shiftable and pivotally connected with the flange *17*. The flange *17* is provided with spaced longitudinal slots *35* and pivot pins *36* on the inner ends of the links *34* slidably and turnably engage in the slots *35*. The pivot pins *36* may be in the nature of rivets or bolts with nuts and shiftable and pivotally secure the links to the flange *17*. The outer ends of the two links *34* are connected by a bolt or pin which I will term the central pivot pin or king pin *37*. A strap or bracket *38* is rigidly fixed to the inner portion of the body *11* at or adjacent its under side and extends from the body to be connected or coupled with the links *34*. As best illustrated in Figs. 1 and 2 of the drawing, the single central pivot pin *37* may serve to connect the two links *34* as well as to connect the body bracket *38* with the links. The nut *39* threaded on the central pivot pin *37* may be adjusted or set to maintain the desired friction between the links *34* and the bracket *38* so that the parts will remain in the adjusted positions until deliberately moved but may be intentionally or deliberately adjusted with ease.

It will be seen that with the structure just described the body *11* may be bodily moved back and forth toward the face of the book in the direction indicated by the arrow *Y* in Fig. 2. During such bodily adjustment of the body *11* the anchoring pivot pins *36* of the links *34* move back and forth in their slots *35*. In this connection it is to be observed that the slots *35* are of sufficient length to allow the body *11* to be adjusted inwardly to an extreme retracted position where it directly overlies the flange *17* and, therefore, is clear of the face of the book and the slots *35* are sufficiently long to allow the body to be moved outwardly a substantial distance from the face of the book so that light from the lamp or bulb *13* may reach all parts of the book face. Furthermore, with the body mounting described above it will be seen that the body *11* and the parts carried thereby may be bodily swung or pivoted about the axis of the central pivot pin *37* to move in the direction indicated by the arrow *X* in Fig. 2. In addition to the two adjustments already described, the body *11* and the parts carried thereby may be bodily moved longitudinally of the book

in the direction indicated by the arrow Z. This is accomplished by merely moving the body so that the hinge pins 36 simultaneously move in their slots 35 in the same direction. This last named adjustment provides for the movement of the source of illumination to selected positions across the face of the book.

The reflector 15 is provided to concentrate the illumination of the bulb or lamp 13 and to direct the light in the manner desired. In accordance with the invention the reflector 15 is mounted on the body 11 for adjustment in various directions and for movement between fully retracted and fully extended positions. The forward end of the shell-like body 11 is open and the body is cut out or provided with a longitudinal lateral aperture 40. The aperture 40 extends from the open end of the body 11 to a point adjacent to or behind the lamp 13. The reflector 15 is an elongate element designed and arranged to telescope over the body 11. The inner end of the reflector 15 is open to receive or engage over the body 11, while the outer end of the reflector is closed. In practice, the closed outer end of the reflector 15 may be rounded or generally spherical. The elongate tube-like reflector 15 is provided with a longitudinally extending lateral aperture 42. The aperture 42 is preferably of substantial length and in practice may extend from the inner end of the reflector 15 to a point adjacent the closed outer end of the reflector. The apertures 40 and 42 are provided to pass or emit the light from the lamp 13 and are preferably of equal width. The inner end of the reflector 15 is interrupted by the lateral aperture 42 and may be equipped with a strengthening ferrule 43.

As illustrated in the drawing the body bracket 33 is on the inner side of the body 11 and the lateral aperture 42 of the reflector 15 is proportioned to readily receive the body bracket 33. Accordingly, the reflector 15 may be shifted rearwardly over the body 11 to a retracted position where its closed outer end is at or adjacent the end of the body 11. In a like manner the reflector 15 may be shifted outwardly on the body 11 to an extended position, such as shown in Figs. 1 and 2 of the drawing. The arrow C in Figs. 1 and 2 indicates the manner in which the reflector 15 may be adjusted longitudinally. In addition to this longitudinal adjustment of the reflector 15 the reflector may be rotated or turned on the body 11 to direct the light in the manner desired. The arrow D indicates the manner in which the reflector 15 may be rotatably adjusted. It is to be understood that the reflector 15 may be turned in either direction to bring its light passing aperture 42 to the desired position. The interior of the reflector 15 may be plated, painted, polished or otherwise finished to have the required light reflecting capabilities.

It will be observed that when the reflector 15 is in its fully retracted position on the body 11 that the over-all length of the body assembly is greatly reduced. In the drawing the device is shown applied to a book of small proportions but where the device is employed on larger books the over-all length of the body assembly with the reflector 15 in its retracted position will be less than the width of the book so that the device will not project beyond the edges of the closed book to interfere with the handling or stacking of the book.

The invention provides a switch means for controlling the light or lamp 13. The switch means is under the control of the reflector 15 and is

such that the lamp 13 is deenergized when the reflector 15 is in the retracted position and is energized when the reflector is in any one of its extended operative positions. The switch means, best illustrated in Fig. 5, includes a plunger 29 of insulation arranged within the shell or body 11 in front of the battery 12. The plunger 29 is arranged for radial movement and has a reduced stem 30 at one end slidably guided in an opening 31 in the wall of the body 11. A spring 32 is arranged under compression at the under side of the plunger 29 and urges the plunger outwardly so that its stem 30 extends into and through the opening 31. The outer end of the stem 30 is rounded for engagement by the reflector 15. A shoulder 53 at the base of the stem 30 limits the outward movement of the plunger 29 and stops the plunger in a position where the stem 30 has its rounded end projecting from the exterior of the body 11.

The switch means further includes the button or contact 28 mentioned above. The contact 28 is secured in the carrier or partition 27, which is formed of insulation, and the forward end of the contact is engaged by the central terminal of the lamp stem 26. The rear end of the contact 28 is exposed at the rear side of the partition 27 and is in spaced opposing relation to the terminal 24 of the battery 12. The switch plunger 29 passes between the terminal 24 and contact 28 in spaced relation thereto and carries contact means for electrically connecting the terminal and contact 28. The plunger 29 carries a bus or connector having a contact 51 at one end for engaging the battery terminal 24 and having a contact 52 at the other end for engaging the lamp contact 28. The contact 51 is preferably shaped to constitute a spring contact which remains in firm engagement with the battery terminal 24 at all times. The contact 52 is movable into and out of engagement with the contact 28 with movement of the plunger 29. The switch means is located so that the stem 30 is engaged and depressed by the reflector 15 when the reflector is retracted and the stem 30 is freed to again project from the body 11 when the reflector is moved to the operative or extended position for use.

When the reflector 15 is retracted the engagement of the reflector with the stem 30 moves the plunger 29 to a position where the contact 52 is out of engagement with the contact 28. When the reflector 15 is moved to an extended position it moves beyond the contact stem 30 and the spring 32 moves the plunger 29 to the position where the contact 52 engages the contact 28 to complete the circuit through the lamp 13. It is to be understood that the parts may be related so that the reflector 15 may be adjusted back and forth to a considerable extent and may be turned to adjust the light as desired and yet hold the switch closed to maintain the lamp 13 energized throughout such adjustments.

It is believed that the utility and practicability of the book lamp provided by the present invention will be readily understood from the foregoing detailed description. To apply the lamp to the book it is merely necessary to engage the plate 16 against the back of the book and to engage the ears 18 with the open face of the book. In this connection it is to be understood that the device may be shifted along the book to any selected position. The body 11 may be grasped and shifted in the direction of the arrow Z to the selected position and pulled out or pushed back to bring it to the selected position in front of the

book. Furthermore, the body 11 may be turned on the pivot pin 37 as required. These various adjustments allow the user to bring the body and the associated parts to any selected positions and the user may position the lamp 13 to the best advantage. The reflector 15 may be extended or adjusted longitudinally and adjusted rotatively to bring its light passing aperture 42 to the selected position. The multiple adjustments of the body 11 and of the reflector 15 assure the positioning of the lamp 13 to the best advantage and the directing of the light as found most desirable. The parts may be adjusted to completely overcome any glare and to adequately illuminate the entire pages P or any selected parts of the pages P. In using the book a page P may be readily disengaged from under its ear 18 and turned and then engaged under the other ear 18. This turning of the pages does not necessitate removal or the disturbing of the lamp in any way. The lamp or device may be easily disengaged from the book when no longer required. The device is very compact and is readily adaptable to and removable from books and the like of various kinds, sizes, etc.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. Means for illuminating a book including a plate part adapted to be engaged behind the book, a flange on the plate part for engaging on the upper edge of the book and having longitudinally spaced slots extending parallel with the upper edge of the book, means on the flange for engaging the pages of the book at opposite sides of the binding to hold the book open, the flange and said means being shiftable as a unit along the upper edge of the book, a body, a lamp carried by the body, a pair of links having their outer ends pivotally connected together, pins carried by the inner ends of the links and shiftably carried by slots in the flange so the links project forwardly from the flange in converging relation, and means for pivotally connecting the outer ends of the links to the body on an axis parallel with the hinge of the book.

2. Means for illuminating a book including an integral sheet metal member having a plate part adapted to be engaged behind the book, a flange projecting up from the upper edge of the plate part for engaging on the upper edge of the book, and spaced projections on the upper edge of the flange for engaging the pages of the book to hold the book open, the said member being shiftable along the upper edge of the book, a body, a lamp carried by the body, a pair of links, means for pivotally and shiftably securing both of the links to the flange to project forwardly

therefrom in converging relation and to be bodily shiftable longitudinally of the flange including longitudinally spaced and disposed slots in the flange and pins on the links slidably held in the slots, means for pivotally connecting the forward ends of the links, means on the body engaged on the last named means supporting the body for pivotal movement, and a reflector for the lamp shiftable along the body.

3. A book lamp comprising mounting means adapted to be applied to the upper edge of a book to extend longitudinally thereof, an elongate body, an electric battery in the body, a lamp stationary with the body at one end thereof to be energized by current from the battery, means for supporting the body on the mounting means for bodily movement therealong and for bodily movement toward and away from the face of the book, a reflector for the lamp slidably mounted on said end of the body to be shiftable longitudinally of the body, and switch means for controlling the lamp operated by longitudinal movement of the reflector on the body.

4. A book lamp comprising mounting means adapted to be applied to the upper edge of a book, an elongate body, an electric battery in the body, a lamp stationary with the body at one end thereof to be energized by current from the battery, means for supporting the body on the mounting means for movement with respect to the book about an axis substantially parallel with the face of the book and transverse of the body, a reflector for the lamp slidably mounted on said end of the body to be shiftable longitudinally of the body between retracted and extended positions and turnable on the body, and switch means for the lamp controlled by movement of the reflector longitudinally relative to the body to deenergize the lamp when the reflector is retracted relative to the body and to energize the lamp when the reflector is extended relative to the body.

5. A book lamp comprising mounting means adapted to be applied to the upper edge of a book, an elongate body substantially round in cross section, an electric battery in the body, a lamp stationary with the body to be energized by current from the battery, means for supporting the body on the mounting means for bodily longitudinal movement therealong and for pivotal movement about an axis extending substantially parallel with the face of the book, an elongate reflector for the lamp shiftable longitudinally on the body between retracted and extended positions and turnable on the body and having a side opening partially closed by the body, and switch means for the lamp controlled by the reflector to deenergize the lamp when the reflector is retracted and to energize the lamp when the reflector is extended, the switch means including a control part engaged by the shiftable reflector.

JACOB COHEN.
